(57) **CLAIM**

I claim, the ornamental design for a needle cartridge clip, as shown and described.

DESCRIPTION

FIG. 1 is a front, top perspective view of a needle cartridge clip;

FIG. 2 is a right side elevation view of the needle cartridge clip illustrated in FIG. 1;

FIG. 3 is a left side elevation view of the needle cartridge clip illustrated in FIG. 1;

FIG. 4 is a rear elevation view of the needle cartridge clip illustrated in FIG. 1;

FIG. 5 is a front elevation view of the needle cartridge clip illustrated in FIG. 1;

FIG. 6 is bottom plan view of the needle cartridge clip illustrated in FIG. 1; and,

FIG. 7 is a top plan view the needle cartridge clip illustrated in FIG. 1.

The broken lines in the drawings illustrate portions of the needle cartridge clip that form no part of the claimed design.

1 Claim, 5 Drawing Sheets
